UNITED STATES PATENT OFFICE

2,585,661

TAILPIECE FOR STRINGED MUSICAL INSTRUMENTS.

John E. Kluson, Chicago, Ill., assignor to Kluson Manufacturing Company, Chicago, Ill., a corporation of Illinois

Application October 26, 1949, Serial No. 123,723

1 Claim. (Cl. 84—299)

1

The present invention relates generally to tail-pieces for stringed musical instruments, such, for example, as guitars. More particularly the invention relates to that type of tailpiece which is mounted on the lower end of the body of the instrument to which it is applied, serves as a medium for anchoring the adjacent ends of the instrument strings, and comprises an attaching bracket, a U-shaped rod, the crosspiece of which is connected by a hinge connection to the bracket and a crossbar which extends between, and is connected to, the free ends of the side pieces of the U-shaped rod and when the tailpiece is in its operative position is disposed beneath the bridge of the instrument.

In a tailpiece of this type it has heretofore been proposed to form a comparatively wide longitudinally extending groove in the lower side portion of the crossbar and transversely extending, laterally spaced, narrow, full length, string receiving notches in the bottom surface of the crossbar and to anchor the adjacent ends of the instrument strings to the crossbar of the tailpiece by attaching such ends to spools and then inserting the spools into the groove and positioning the strings in the notches. In practice it has been found that a tailpiece, the crossbar of which has the adjacent ends of the strings anchored to it in the aforementioned manner, is objectionable because anchoring of the adjacent ends of the strings to the crossbar of the tailpiece is difficult due to the fact that when the strings are not under tension there is a marked tendency for the spools to drop by gravity from seated relation with the longitudinal groove in the lower side portion of the crossbar.

The principal object of this invention is to provide a stringed instrument tailpiece which is an improvement upon, and eliminates the objection to, previously designed tailpieces of the aforementioned type and is characterized by the fact that it embodies novel means whereby the adjacent ends of the strings are anchored to the crossbar of the tailpiece without likelihood of displacement of the spools from seated relation with the crossbar when the strings are not subject to tension.

A further object of the invention is to provide a stringed instrument tailpiece which effectively and efficiently fulfills its intended purpose, and is capable of being produced at a comparatively low cost.

Other objects of the invention and the various advantages and characteristics of the present tailpiece for stringed musical instruments will be

apparent from a consideration of the following detailed description.

The invention consists in the several novel features which are hereinafter set forth and are more particularly defined by the claim at the conclusion hereof.

In the drawing which accompanies and forms a part of this specification or disclosure and in which like letters and numerals of reference denote corresponding parts throughout the several views:

Figure 1 is a plan view of a stringed instrument having applied thereto a tailpiece embodying the invention:

15 Figure 2 is an enlarged view showing the bracket and U-shaped rod of the tailpiece in plan and the crossbar in horizontal section and illustrating in detail the construction and design of the means for anchoring the spool equipped ends 20 of the strings of the instrument to the crossbar;

Figure 3 is a vertical longitudinal section on the line 3-3 of Figure 1;

Figure 4 is an enlarged perspective view of the free end of one of the side pieces of the U-shaped rod;

Figure 5 is an enlarged horizontal section on the line 5—5 of Figure 3; and

Figure 6 is a perspective of one of the spools for use in anchoring the strings of the instrument to the crossbar of the tailpiece.

The tailpiece which is shown in the drawing constitutes the preferred form or embodiment of the invention. It is illustrated as being applied to, and forming a part of, a guitar G and, as hereinafter described more in detail, serves as a medium or instrumentality for anchoring the strings *g* of the guitar. The guitar G is of conventional or standard construction and represents but one type of stringed instrument to which the tailpiece may be applied. As shown in Figure 1, the guitar G comprises a hollow body *g*¹ and a neck *g*². The latter is connected to, and projects outwards from, the so-called upper end of the body and consists of a shank part and a head part at the outer end of the shank part. The shank part

49 other end of the shank part. The shank part of the neck has the usual keyboard with its upper surface and the strings g extend lengthwise over the keyboard. The head part of the neck g^2 embodies tuning heads g^3 and these correspond in 50 number to, and are connected to the adjacent ends of, the strings g . The neck embodies between the shank and the head parts a notched extension nut g^4 over which the strings g extend. The body g^1 of the guitar G embodies a top wall 55 g^5 and a continuous side wall g^6 and is provided

on its top wall with an upstanding bridge g^7 . The latter is disposed between the lower end of the body top wall g^6 and the lower end of the shank part of the neck g^2 and serves to support above the top wall g^5 of the body the ends of the strings that are anchored to the tailpiece. The strings g are formed of wire and have the last mentioned ends thereof attached to spools g^8 . The latter, as shown in Figure 6, have tapered ends and circumferential grooves intermediate or midway between their ends. The strings g are connected to the spools by wrapping or bending around the grooves in the spools the ends that are to be anchored to the tailpiece and then twisting the end extremities around the adjacent portions of the strings as best shown in Figure 5 of the drawing. The spools g^8 are arranged so that the axes thereof extend at right angles to the strings, and are materially greater in length than the strings are thick.

As its components or parts the tailpiece comprises a bracket 7 , a U-shaped rod 8 and a crossbar 9 .

The bracket 7 serves as an attaching medium for the tailpiece, is preferably in the form of a one-piece sheet metal stamping and consists of a pair of parts 10 and 11 . The bracket part 10 is substantially flat and fits against the upper portion of the lower end of the side wall g^6 of the guitar body g^1 and is secured in place by means of screws 12 or similar attaching devices. The other part of the bracket 7 , i. e., the part 11 , is connected to the upper end of the part 10 and extends upwards and inwards with respect to the bracket part 10 . The outer end of the bracket part 11 is bent to form an open ended, cylindrical sleeve 13 which, as shown in Figure 3, extends transversely to the guitar body g^1 and is spaced a small distance above the body top wall g^5 .

The U-shaped rod 8 of the tailpiece is formed of stiff or rigid metallic stock and is located between the bracket 7 and the bridge g^7 . It is disposed above and in substantially parallel relation with the top wall g^5 of the guitar body and consists of a straight crosspiece 14 and a pair of side pieces 15 . The crosspiece 14 extends loosely through the sleeve 13 with the result that the U-shaped rod 8 is connected by a hinge connection to the bracket and is free to swing upwards and downwards with respect to the top wall of the body in connection with anchoring of the strings g to the tailpiece. The side pieces 15 of the U-shaped rod 8 are connected by substantially right angle bends to the ends of the crosspiece 14 . The portions of the side pieces other than the outer ends are outwardly divergent and the outer ends of the side pieces are in parallel relation as shown in Figures 1 and 2. The stock of which the U-shaped rod is formed is of circular cross section.

The crossbar 9 of the tailpiece extends between the free ends of the side pieces 15 of the U-shaped rod 8 and is formed of any suitable hard material, such, for example, as steel. It is arched to a comparatively small extent, as shown in Figure 3 and embodies a plurality of equidistantly spaced, transversely extending, bore-formed holes 16 . The latter correspond in number to, and are adapted respectively to receive the adjacent ends of, the strings g of the guitar G . They are disposed midway between the top and bottom faces of the crossbar 9 and extend between and through the side faces of the crossbar. The ends of the holes 16 that are adjacent the side face of the crossbar that is in opposed relation with the bracket

7 are counter-bored to form cylindrical sockets 17 for receiving the spools g^8 on the adjacent ends of the strings g . As shown in Figures 2, 3 and 5, the diameter of the sockets 17 is slightly greater than the length of the spools and the depth of the socket is slightly greater than the width or diameter of the spools. The inner ends of the sockets are tapered or countersunk conformably to the tapered ends of the spools and as a result when the strings g are under tension said inner ends of the sockets coact with the tapered ends of the spools to center the spools with respect to the sockets and thus maintain the anchored ends of the strings in centered relation with the bore formed holes 16 . When it is desired to anchor the strings g of the guitar G to the crossbar 9 of the tailpiece the ends of the strings that are adapted for connection to the tuning heads g^3 on the head part of the guitar neck g^2 are first inserted into the sockets 17 and are then passed or threaded through the bore formed holes 16 . Thereafter the strings are pulled away from the tailpiece until the spools g^8 are brought within the sockets 17 . When the spools are disposed within the sockets the spool ends coact with the portions of the crossbar that define the inner ends of the socket to limit movement of the spool equipped ends of the strings in the direction of the bridge g^7 . After insertion of the strings through the holes 16 and lodgment or disposition of the spools g^8 in the sockets 17 the other ends of the strings are connected to the tuning heads g^3 . By providing the holes 16 and enlarged sockets 17 in the crossbar 9 of the tailpiece the spool equipped ends of the strings g remain in anchored or interfitting relation with the crossbar regardless of whether the strings are subjected to tension. In other words, after the strings are inserted through the holes 16 the spool equipped ends thereof cannot become dislodged or disconnected from the crossbar of the tailpiece even though the other ends of the strings are not connected to the tuning heads on the head part of the guitar neck g^2 . By having the sockets 17 as deep as the spools g^8 are wide the spools, when the strings are under tension, are disposed wholly within the crossbar 9 and hence do not form protuberances which would interfere with playing of the guitar.

The ends of the crossbar 9 of the tailpiece are provided with transverse bore formed holes 18 . The latter are adapted to receive the free ends of the side pieces 15 of the U-shaped rod 8 and extend between and through the side faces of the crossbar. The ends of the holes that are adjacent the side face of the crossbar that is in opposed relation with the bridge g^7 are counter-bored to form enlarged sockets 19 , the inner ends of which are defined by flat annular shoulders 20 . The extremities of the free ends of the side pieces 15 are compressed laterally to form integral enlargements 21 which fit within the sockets 19 and abut against the shoulders 20 , as shown in Figure 2. The enlargements 21 are normally of greater width than the sockets 19 in order that when the crossbar is in proper connected relation with the U-shaped rod 8 they engage the sockets with a press or drive fit and hence hold the crossbar against sliding movement in either direction with respect to the U-shaped rod. The enlargements 21 coact with the shoulders 20 positively to prevent sliding movement of the crossbar 9 relatively to the U-shaped rod 15 in the direction of the bridge g^7 and hence when the tailpiece is in use there is no likelihood

hood whatsoever of the crossbar shifting or sliding towards the bridge g' and resultantly effecting a change in the tuning of the strings g . In assembling the tailpiece the crosspiece 14 of the U-shaped rod 8 is connected to the bracket part 11 by introducing it into the sleeve 13 . This is done before the extremities of the free ends of the side pieces of the U-shaped rod are compressed to form the enlargements 21 . After connection of the U-shaped rod to the bracket 7 the crossbar 9 is manipulated so as to align the holes 18 in its ends with the free ends of the side pieces of the U-shaped rod. Thereafter the crossbar is shifted towards the U-shaped rod in order to effect insertion of the free ends of the side pieces completely through the bore formed holes 18 . After this operation the extremities of the free ends of the side pieces are compressed to form the enlargements 21 and thereafter the crossbar 9 is driven away from the bracket 7 in order to bring the enlargements 21 into the enlarged sockets 19 and cause them to grip the sockets with a so-called press or drive fit. After assembly of the tailpiece and application of the latter to the guitar the strings g are anchored to the crossbar 9 as hereinbefore described.

The herein described tailpiece effectively and efficiently fulfills its intended purpose and is characterized by the fact that the bore formed holes 16 and the enlarged sockets 17 constitute such means for anchoring the adjacent ends of the strings to the tailpiece crossbar that such ends are always in connected relation with the crossbar regardless of whether the strings are under tension.

Whereas the tailpiece has been described and illustrated in connection with a guitar it is to be understood that it may be applied to other types of stringed musical instruments. It is also to be understood that the invention is not to be restricted to the details set forth since these may be modified within the scope of the appended claim without departing from the spirit and scope of the invention.

Having thus described the invention what I claim as new and desire to secure by Letters Patent is:

As a new article of manufacture, a tailpiece

designed for use on a stringed musical instrument of the type that embodies a body and neck with a plurality of laterally spaced strings extending lengthwise over the body and neck and having the ends thereof that are adjacent the body connected to the central portions of elongated transversely extending substantially cylindrical spools with outwardly tapered ends, said tailpiece comprising a bracket provided with means for attachment to the lower end of the body and an elongated crossbar connected to the bracket so that when the tailpiece is in place on the instrument it overlies, and extends transversely of, the body, and having formed therein a plurality of laterally spaced open ended but closed sided cylindrical holes extending longitudinally of the body, corresponding in number to the strings, adapted respectively to have threaded therethrough said ends of the strings, and provided at the ends thereof that are remote from the instrument neck with enlarged cylindrical concentrically arranged sockets for seating and completely housing said spools, the inner ends of the sockets being tapered in the direction of the neck of the instrument in order that when the strings are placed under tension the portions of the crossbar that define said inner ends of the sockets coat with the tapered ends of the spools to center the spools with respect to said sockets and also center the strings within their respective holes in the crossbar.

JOHN E. KLUSON.
